US00D846122S

(12) **United States Design Patent** (10) Patent No.: **US D846,122 S**
Pintor (45) Date of Patent: **** Apr. 16, 2019**

(54) **HEART VALVE SIZER**

(71) Applicant: **Edwards Lifesciences Corporation**,
 Irvine, CA (US)

(72) Inventor: **Rafael Pintor**, Mission Viejo, CA (US)

(73) Assignee: **Edwards Lifesciences Corporation**,
 Irvine, CA (US)

(**) Term: **15 Years**

(21) Appl. No.: **29/588,016**

(22) Filed: **Dec. 16, 2016**

(51) LOC (11) Cl. **24-02**

(52) U.S. Cl.

USPC **D24/140**
